UNITED STATES PATENT OFFICE

WILLIAM C. HAGAN, OF KINGSTON, PENNSYLVANIA

POWER CYLINDER AND PISTON

Application filed July 15, 1931. Serial No. 551,004.

This invention relates to a power cylinder and piston for use with any suitable fuel or actuating fluid and has for its primary object to provide, in a manner as hereinafter set forth, a power cylinder and piston embodying a novel construction, combination and arrangement of parts, whereby a materially greater degree of efficiency is had.

Other objects of the invention are to provide a power cylinder and piston of the character described which will be simple in construction, strong, durable, reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in top plan of a power cylinder and piston in accordance with this invention.

Figure 2 is a view in vertical section therethrough.

Figure 3 is a view in horizontal section taken substantially on the line 3—3 of Figure 2, looking downwardly, as indicated by the arrows.

Figure 4 is a view in side elevation of the piston and the lower portion of the trailer.

Figure 5 is a detail view in vertical section through the piston without the stepped depression.

Figure 6 is a detail view in bottom plan of the piston.

Figure 7 is a detail view in vertical section through a solid form of trailer.

Referring now to the drawings in detail it will be seen that the reference numeral 1 designates a cylinder of uniform diameter throughout having formed integrally on its upper and lower ends the apertured, external flanges 2 and 3, respectively. The flange 3 is for connection with a suitable crank case, a portion of which is designated by the reference numeral 4. The cylinder 1 is open at its ends.

The reference numeral 5 designates a head which is also open at its ends, said head being of less diameter than the cylinder 1 and having an outwardly and then downwardly directed flange 6 on its lower end engaged on the flange 2 of the cylinder. The head 5 has a bore of smaller diameter than the bore of the cylinder 1. Bolts 7 extend through openings provided therefor in the flange 6 and are threaded into the flange 2 for removably securing the head 5 in position. The lower portion of the head 5 is internally grooved for receiving the packing rings 8. The upper portion of the head 5 is enlarged and is provided with an internal, annular reservoir 9 for the reception of lubricating oil which is deposited in the reservoir through a port 10 provided for the purpose in the top of the head. The port 10 is normally closed by a threaded closure plug 11.

The reference numeral 12 designates a piston which is mounted for reciprocation in the cylinder 1, a diametrically extending wrist pin 13 being mounted in the skirt portion of said piston upon which a connecting rod 14 is journaled. The piston 12 is provided with a solid head portion 15 having a stepped recess or depression 16 therein. Fig. 5 shows that the piston may be employed without this stepped depression 16. A trailer 17 is operable in the cylinder 1 and extends slidably through the head 5, said trailer having a tapered lower end portion 18 for disposition in the stepped depression 16 and terminating in a threaded shank 19 for insertion through an opening provided therefor centrally in the head portion 15. A retaining nut 20 is threaded on the shank 19 for connecting the trailer 17 to the piston 12 for reciprocation therewith. It will be noted that the trailer 17 is spaced inwardly from the cylinder 1 and that the lower end portion 18 of said trailer is spaced from the stepped walls of the depression 16. The trailer 17 is disposed concentrically in the cylinder 1. The piston 12 is circumferentially grooved at spaced points for the reception of suitable rings 21.

It will be noted that the trailer 17 is hollow and open at its upper end, thus making

for economy in material and lightness in weight. However, if desired, a solid trailer 22 as seen in Figure 7 of the drawings may be provided. In addition to other functions, 5 the trailers 17 and 22 provide a reciprocating guide for the piston 12 in the cylinder 1 with the result that the tendency to wear untrue due to lateral thrust by the connecting rod will be reduced on the piston and 10 the cylinder, as will be obvious.

It is believed that the many advantages 15 of a structure in accordance with the present invention will be readily understood, and although the preferred embodiment of the invention is as illustrated and described, it 20 is to be understood that changes in the details of construction and in combination and arrangement of parts may be resorted to which will fall within the scope of the invention as claimed.

What is claimed is:-

A cylinder open at its ends, a head having 25 a bore of smaller diameter than the bore of the cylinder, mounted on one end of said cylinder, said head being open at its ends, 30 a piston mounted for reciprocation in the cylinder, said piston comprising a solid head portion having a stepped depression therein and further having a centrally disposed opening in the head portion thereof, and a trailer, operable in the cylinder and slideable through the head, rigidly connected to the piston for reciprocation therewith, said trailer being spaced inwardly and concentrically 35 from the cylinder and including a tapered end portion disposed in the depression in spaced, concentric relation to the stepped walls of said depression, a threaded shank projecting from the tapered end of the trailer, said shank disposed through the opening 40 in the edge portion of the piston, and a retaining nut threaded on the shank for connecting the trailer to the piston.

In testimony whereof I affix my signature.

WILLIAM C. HAGAN.
